(57) **CLAIM**

The ornamental design for a wall organizer kit, as shown and described.

DESCRIPTION

FIG. 1 is a perspective view of a wall organizer kit including a rail, a hat stand, and a perch showing the design in an exemplary arrangement on a wall;

FIG. 2 is a perspective view of the rail of FIG. 1;

FIG. 3 is a front elevational view of the rail of FIG. 1;

FIG. 4 is a rear elevational view of the rail of FIG. 1;

FIG. 5 is a right elevational view of the rail of FIG. 1;

FIG. 6 is a left elevational view of the rail of FIG. 1;

FIG. 7 is a top plan view of the rail of FIG. 1;

FIG. 8 is a bottom plan view of the rail of FIG. 1;

FIG. 9 is a perspective view of the hat stand of FIG. 1;

FIG. 10 is a front elevational view of the hat stand of FIG. 1;

FIG. 11 is a rear elevational view of the hat stand of FIG. 1;

FIG. 12 is a right elevational view of the hat stand of FIG. 1;

FIG. 13 is a left elevational view of the hat stand of FIG. 1;

FIG. 14 is a top plan view of the hat stand of FIG. 1;

FIG. 15 is a bottom plan view of the hat stand of FIG. 1;

FIG. 16 is a perspective view of the perch of FIG. 1;

FIG. 17 is a front elevational view of the perch of FIG. 1;

FIG. 18 is a rear elevational view of the perch of FIG. 1;

FIG. 19 is a right elevational view of the perch of FIG. 1;

FIG. 20 is a left elevational view of the perch of FIG. 1;

FIG. 21 is a top plan view of the perch of FIG. 1;

FIG. 22 is a bottom plan view of the perch of FIG. 1;

FIG. 23 is a front elevation view of the wall organizer kit of FIG. 1 in an exemplary arrangement on a wall; and,

FIG. 24 is a front elevation view of the wall organizer kit of FIG. 1 in another exemplary arrangement on a wall.

The broken lines in the drawings are for the purpose of illustrating environment and form no part of the claimed design. The symbolic break lines in the drawings are used to

(Continued)

indicate that any portion of the wall organizer kit between the break lines forms no part of the claimed design.
